His attorney

UNITED STATES PATENT OFFICE

LEWIS L. NETTLETON, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA

ELECTRORESPONSIVE APPARATUS

Application filed February 5, 1924. Serial No. 690,830.

My invention relates to electro-responsive apparatus, and particularly to apparatus of the type including a relay having a tuned vibrating member.

5 One object of my invention is the provision of apparatus which will not result in a false indication if the tuned vibrating member sticks in an improper position when the relay is not energized.

10 I will describe several forms of apparatus embodying my invention and will then point out the novel features thereof in claims.

In the accompanying drawings, Fig. 1 is a view, partly diagrammatic, showing one 15 form of apparatus embodying my invention. Figs. 2 and 3 are views showing modifications of a portion of the apparatus shown in Fig. 1 and also embodying my invention.

Referring first to Fig. 1, the apparatus includes a relay R having a vibrating armature V, which armature is mechanically tuned by a spring support S and an adjustable weight W to the frequency of the alternating current by which it is intended that the relay 20 should be operated. This armature V is polarized by suitable means, and, as here shown, this is accomplished by a coil P constantly supplied with current by a battery 22. The relay R further comprises a U-shaped field member 11 carrying two operating coils C, C. The armature V controls a contact K in such manner that this contact is open when the armature is at rest in its intermediate position, but is intermittently closed when the armature is vibrating.

The operating coils C are supplied with current in any suitable manner, as, for example, by means of a winding A in which alternating current is induced. This winding A may, for example, be the pick-up winding in inductive relation with the track rail or an axle transformer in an automatic train controlling system. The winding A is normally supplied with alternating current 40 only of the frequency for which the relay R is tuned, but if desired, the circuit for winding A may be provided with condensers 10 and 10^a, so that the circuit functions to freely transmit current of the predetermined frequency and to prevent transmission of cur-

rents of other frequencies to the operating coils C.

The contact K controls a relay D, the circuit for which passes from a battery B, through spring support S, armature V, contact K, and the winding of relay D to battery B. Relay D is provided with two armatures, 12 and 18. The relay is so designed and proportioned that the armature 12 will be closed, that is, contact F' will be closed, when the relay is energized due to intermittent operation of the contact K at the predetermined frequency, but that during such energization the armature 18 remains retracted so that contact F is closed. The relay is further designed and proportioned, however, in such manner that if by accident the relay is energized due to sustained closure of contact K, armature 18 will be attracted so that contact F will open. The relay D controls an electro-responsive device E, the circuit for which passes from a battery 16, through contact F, contact F' and device E to battery 16.

It will be seen from the foregoing that as long as contact K is open, relay D will be de-energized, so that its contact F' will be open, and, consequently, the device E will not be energized. When relay R is supplied with alternating current, so that armature V is caused to vibrate, contact K will be intermittently closed, whereupon relay D will be energized in such manner that contacts F' and F are both closed; the device E will then be energized. If the armature V should stick in such position that contact K remains closed, relay D will be energized in such manner that contact F' will be closed and contact F will be opened, so that the device E will then be de-energized. It will be seen, therefore, that the apparatus shown in Fig. 1 functions to prevent false energization of the device E due to sustained closure of contact K in relay R.

Referring now to Fig. 2, the apparatus in the form here shown, comprises an induction motor relay L controlled by contact K of relay R. The relay L comprises two stator windings 13 and 13^a connected in series and included in circuit with battery B and con-

tact K. A condenser 14 is connected with winding 13^a through the medium of a transformer 15 for the purpose of displacing the phases of the currents in the two windings of relay L. When armature V is vibrating the intermittent closing of contact K causes pulsating current to be supplied to the windings of relay L, which current energizes this relay and causes it to close its front contact 17—17^a. In the event, however, that the armature V sticks in such position that contact K is closed, the windings of relay L will be supplied with continuous current by battery B, and since this relay is of the induction motor type it will not respond to such current and so its front contact 17—17^a will be open.

Referring now to Fig. 3, the contact K controls a circuit including a battery B and 20 the primary of a transformer T. The secondary of this transformer supplies current to a rectifying device J, which in turn supplies uni-directional current to a relay D. When armature V is vibrating, the pulsating 25 current in the primary of transformer T induces alternating current in the secondary of this transformer, which alternating current is rectified, of course, by the device J. If contact K sticks in the closed position, 30 however, continuous current will be supplied to the primary of transformer T and so the secondary circuit of this transformer will be de-energized, with the result that no current will be supplied to relay D.

35 It will be seen from the foregoing that the apparatus shown in Figs. 2 and 3, as well as the apparatus shown in Fig. 1, guards against false energization of the electro-responsive device due to continued closure of 40 contact K of the tuned vibrating relay R.

Although I have herein shown and described only three forms of apparatus embodying my invention, it is understood that various changes and modifications may be 45 made therein within the scope of the appended claims without departing from the spirit and scope of my invention.

Having thus described my invention, what I claim is:

50 1. In combination, a normally open contact, means for causing intermittent operation of said contact, a circuit including said contact and a source of current, a controlled device, and means associated with said circuit for causing said device to respond to intermittent operation of said contact but not to sustained closure thereof.

55 2. In combination, a contact, means for causing intermittent operation of said contact, a circuit including said contact and a source of current, and a magnet included in said circuit and provided with two armatures one of which is closed when the magnet is energized due to intermittent operation 60 of said contact and the other of which

is closed only when the magnet is energized due to sustained closure of said contact.

3. In combination, a relay comprising an armature mechanically tuned to vibrate at a given frequency, means for supplying periodic current of said given frequency to said relay, a contact operated by said armature, a circuit including said contact and a source of current, a controlled device, and means associated with said circuit for causing said device to respond to intermittent operation of said contact but not to sustained closure thereof. 75

4. In combination, a relay comprising an armature mechanically tuned to vibrate at a given frequency, means for supplying periodic current of said given frequency to said relay, a contact operated by said armature, a circuit including said contact and a source of current, a controlled device, and means for causing said device to respond to periodic current but not to continuous current in said circuit. 80

5. In combination, a normally open contact, means for causing intermittent operation of said contact, a circuit including said contact and a source of current, a controlled device, and means for causing said device to respond to periodic current but not to continuous current in said circuit. 90

6. In combination, a contact, means for causing intermittent operation of said contact, a circuit including said contact and a source of current, and a magnet included in said circuit and provided with two armatures one of which is attracted when the magnet is energized due to intermittent operation of said contact and the other of which is attracted only when the magnet is energized due to sustained closure of said contact, an electro-responsive device, and a circuit for said device including in series a contact closed only when said first armature is closed and a contact closed only when said second armature is open. 100

7. In combination, a relay comprising an armature mechanically tuned to vibrate at a given frequency and biased to an intermediate position, a contact open when said armature is at rest in said intermediate position but periodically closed while the armature is vibrating, a circuit including said contact and a source of current, means for supplying periodic current of said given frequency to said relay, a controlled device and means associated with said circuit for causing said device to respond to intermittent operation of said contact but not to sustained closure thereof. 110

8. In combination, a relay comprising an armature tuned to vibrate at a given frequency, means for supplying periodic current of said frequency to said relay, a contact operated by said armature, a circuit including said contact and a source of current, 125

- electro-responsive means included in said circuit and controlling two auxiliary contacts one of which closes in response to intermittent operation of the first contact and the 5 other of which opens in response to sustained closure of the first contact but not to intermittent operation of said first contact, and a controlled circuit governed by said two auxiliary contacts.
- 10 9. In combination, a relay comprising an armature tuned to vibrate at a given frequency and biased to an intermediate position, a contact open when said armature is at rest in its intermediate position but periodically 15 closed while the armature is vibrating, a circuit including said contact and a source of current, electro-responsive means included in said circuit and controlling two auxiliary contacts one of which closes in response to 20 intermittent operation of the first contact and the other of which opens in response to sustained closure of the first contact but not to intermittent operation of said first contact, and a controlled circuit governed by 25 said two auxiliary contacts. 75
10. In combination, a contact, means for causing intermittent operation of said contact, a circuit including said contact and a source of current, a controlled device and an 30 induction motor supplied with energy by said circuit for causing said device to respond to intermittent operations of said contact but not to sustained closure thereof. 80
11. In combination, a contact, means for 35 causing intermittent operation of said contact, a circuit including said contact and a source of current, a controlled device, and a transformer the primary of which is included in said circuit, and the secondary of which 40 is connected with said controlled device for causing said device to respond to intermittent operation of said contact but not to sustained closure thereof. 85
12. In combination, a relay comprising an 45 armature mechanically tuned to vibrate at a given frequency, means for supplying periodic current of said given frequency to said relay, a contact operated by said armature, a circuit including said contact and a source 50 of current, a controlled device, and a transformer the primary of which is included in said circuit, and the secondary of which is connected with said controlled device for causing said device to respond to intermittent 55 operation of said contact but not to sustained closure thereof. 90
13. In combination, a contact, means for 60 causing intermittent operation of said contact, a circuit including said contact and a source of current, a transformer the primary of which is included in said circuit, a rectifier associated with the secondary circuit of said transformer, and a controlled device responsive to uni-directional current receiving 65 energy from said rectifier, whereby said de- 95
- vice responds to intermittent operation of said contact but not to sustained closure thereof. 100
- In testimony whereof I affix my signature. 105
